UNITED STATES PATENT OFFICE

120,360

DESIGN FOR A PRESS UNIT FRONT

Thomas F. Stacy, Piqua, Ohio, assignor to The French Oil Mill Machinery Company, Piqua, Ohio

Application January 4, 1940, Serial No. 89,304

Term of patent 14 years

To all whom it may concern:

Be it known that I, Thomas F. Stacy, a citizen of the United States, residing at Piqua, county of Miami, and State of Ohio, have invented a new, original, and ornamental Design for a Press Unit Front, of which the following is a specification, reference being had to the accompanying drawing, forming a part thereof.

The figure is a perspective of a press unit front embodying and showing my new design.

Both ends of the unit have the same appearance, and the rear face of the unit above the base is open.

I claim:

The ornamental design for a press unit front, substantially as shown and described.

THOMAS F. STACY.
